UNITED STATES PATENT OFFICE.

JAMES B. RYAN, OF NEW YORK, N. Y.

CORSET.

SPECIFICATION forming part of Letters Patent No. 664,294, dated December 18, 1900.

Application filed February 23, 1900. Serial No. 6,242. (No model.)

To all whom it may concern:

Be it known that I, JAMES B. RYAN, a citizen of the United States, residing at New York, in the county of New York and State of New York, have invented new and useful Improvements in Corsets and the Like, of which the following is a specification.

My invention relates to corsets and other articles of personal apparel adjustable at the back or side of the body; and it consists in the peculiar and advantageous construction hereinafter described, and particularly pointed out in the claims appended, whereby the wearer of such articles is enabled to quickly and conveniently adjust, tighten, and fasten the same upon his or her body and whereby the adjusting and fastening means may be readily lengthened or shortened either in whole or in part, so as to enable such means to properly fit a corset or two-part article of apparel to bodies of different shapes and sizes.

The invention also consists in the peculiar and advantageous adjusting and fastening means which is susceptible of being placed on the market as an improved article of manufacture and readily applied to and used in conjunction with ordinary corsets and other two-part or sectional articles of personal wear.

With the foregoing in mind the invention will be fully understood from the following description and claims when taken in conjunction with the accompanying drawings, in which—

Figure 1 is a rear elevation of an ordinary two-part corset equipped with my improvements. Figs. 2, 3, 4, and 5 are detail elevations of modifications.

Referring by letter to the said drawings, and more particularly to Fig. 1 thereof, A A are the sections of an ordinary two-part corset, which are provided adjacent to their rear edges with the usual vertical series of eyelets a, and B B are the cords of my improved adjusting, tightening, and fastening means. These cords B are each passed loosely through opposite or complementary eyelets a of the corset-sections A and have their opposite ends connected to the rear ends of waistband or belt sections C D, which are normally located about midway of the height of

the corset and are provided at their forward ends with suitable coacting connecting devices such as illustrated. By virtue of this construction it will be observed that the user of a corset is enabled, after placing the corset on the body, to quickly and conveniently tighten and fasten the same, this being done by simply drawing the waistband or belt sections C D forwardly and connecting the forward ends of the same. It will also be seen that when the belt-sections C D are drawn forwardly the rear edges of the sections A A are pulled together uniformly throughout the height of the corset and are flexibly connected together in such manner as to enable each of them to snugly conform to and properly fit the body, and, furthermore, that when the belt or belt-sections are pressed upwardly the corset will be rendered loose at its upper end and correspondingly tight at its lower end, while when the said belt-sections are pressed downwardly the opposite result will be accomplished.

The rear end of the waistband or belt section C is permanently connected to one end of each of the connecting-cords B, while the rear end of the belt-section D is detachably and adjustably connected to the opposite ends of the several cords, preferably through the medium of an ordinary suspender-buckle E, secured on the section D, as shown in Fig. 1. This construction is advantageous—first, because it admits of the adjusting and fastening means being placed on the market as an article of manufacture and readily applied to corsets, shoulder-braces, and other two-part articles of wearing-apparel such as at present in use, and, second, because it permits of any one or more of the cords being shortened to take up slack thereof or to render one part of the corset or other article tighter than the remainder thereof, as is sometimes desirable.

In order to apply the improved adjusting and fastening means to an ordinary corset, for instance, it is simply necessary to pass the free ends of the cords B through complementary eyelets a in the corset-sections A A after the manner shown in Fig. 1 and then connect the said free ends to the belt-section D through the medium of the buckle E there-

on, when the corset is rendered complete and ready for use. From this it follows that my improved adjusting and fastening means may be applied to an ordinary corset or similar sectional article of wearing-apparel quite as readily as the ordinary lace and that when it is properly applied the corset is rendered far superior to those the sections of which are connected by non-adjustable continuous laces, such as used in shoes, which snap and break by reason of their being laced too loose in some parts and too tight in others and which are also objectionable because they wear unevenly and are liable to be broken after a short period of use.

While the adjusting and fastening means comprising the buckle E is susceptible of being placed on the market as an article of manufacture and applied to corsets and similar articles of apparel, I desire it distinctly understood that I contemplate applying such means to corsets and similar articles at the time of manufacture, as it is a simple, inexpensive, and durable embodiment of my invention.

In Figs. 2 and 3 of the drawings I have illustrated modified belt-sections D' D², to which the ends of the cords B are permanently connected. The belt-section D' is provided with one or more hooks E', and hence when it is desired to shorten one or more of the cords B to take up slack of the same or to render one part of the corset tighter than the remainder thereof the same may be accomplished by looping such cord or cords over the hooks. The belt-section D² is provided with a button E² for the same purpose as the hooks E' of section D', one or more of the cords B being looped or wound around the said button when it is desired to shorten the same.

When desirable, one or both of the belt-sections may be provided at their rear ends with eyelets a', such as shown in Fig. 4, and the cords may be connected to said section or sections in a detachable and adjustable manner by being passed through the eyelets a' and provided with knots or other enlargements. This construction permits of the cords being readily adjusted, it being simply necessary when it is desired to shorten a cord to draw

it through an eyelet of one belt-section to the extent desired and provide it with a new knot.

In Fig. 5 I have illustrated a modification in which the cords are provided with bent hooks b' to engage the eyes a' of one or both belt-sections.

Having thus described my invention, what I claim is—

1. In a corset or other sectional article of personal apparel, the combination with the sections having eyelets adjacent to their edges; of adjusting and fastening means comprising cords passed through complementary eyelets of the sections, a belt-section connected to one end of each of the cords, and a belt-section, at the opposite ends of the cords, provided with cord-engaging means arranged to permit of the separate and independent lengthwise adjustment of the cords, substantially as and for the purpose set forth.

2. In a corset or other sectional article of personal apparel, the combination with the sections having eyelets adjacent to their edges; of adjusting and fastening means comprising cords passed through complementary eyelets of the sections, a belt-section connected to one end of each of the cords, a second belt-section, and a fastening device on the latter belt-section detachably connecting the opposite ends of the cords thereto, said fastening device being arranged to permit of the separate and independent lengthwise adjustment of the cords, substantially as and for the purpose set forth.

3. As an improved article of manufacture, the adjusting and fastening means described, comprising a plurality of cords, a belt-section connected to one end of each of the cords, and a second belt-section provided with cord-engaging means arranged to permit of the separate and independent lengthwise adjustment of the cords, and the disconnection thereof, substantially as specified.

In testimony whereof I have hereunto set my hand in presence of two subscribing witnesses.

JAMES B. RYAN.
